UNITED STATES PATENT OFFICE.

ARTHUR I. FISCHER, OF CLEVELAND HEIGHTS, OHIO, ASSIGNOR TO MORRIS H. GLAUBER, OF CLEVELAND, OHIO.

COMBINED WATER SUPPLY AND OVERFLOW FIXTURE FOR BATHTUBS.

Application filed September 28, 1923. Serial No. 665,330.

To all whom it may concern:

Be it known that I, ARTHUR I. FISCHER, a citizen of the United States, residing at Cleveland Heights, in the county of Cuyahoga and State of Ohio, have invented certain new and useful Improvements in a Combined Water Supply and Overflow Fixture for Bathtubs, of which the following is a specification.

10 My invention relates to improvements in a combined water supply and over-flow fixture for bath tubs, and my general object is to provide a fixture of that kind constructed of cast-metal and porcelain, vitreous china or enameled material for attachment and use with porcelain or enameled bath tubs and similar lavatory receptacles. Furthermore the device is constructed in a particular way to effect convenient and safe attachment to 15 the tub, and also convenient adjustment in fitting the respective parts to tubs having inclined end walls.

In the accompanying drawings, Fig. 1 is a vertical section of the end portion of a 20 bath tub, showing my improved fixture attached thereto.

Fig. 2 is a vertical section transversely of the bath tub and a front elevation of the fixture parts within the tub.

25 Figs. 3 and 4 are section and perspective views, respectively, of the hollow cast-metal head or main coupling member of the fixture.

Figs. 5 and 6 are section and perspective 30 views, respectively, of the hooded overflow plate which is used as a front clamping member for the fixture or fitting.

Fig. 7 is an enlarged vertical section centrally through the head and the clamping 35 hood affixed to the wall of a bath tub and connected with an overflow discharge pipe.

Fig. 8 is a rear elevation and vertical section on line 8—8 of Fig. 7, showing the discharge pipe in dotted and full lines in different angular positions.

The invention comprises a cast-metal hollow head 2 having the form of an elbow, one 40 end of which is turned downwardly and provided with external screw-threads 3 and an internal end seat or socket 4. This end socket is spherically rounded to receive a rounded or partly spherical collar or terminal member 5 which is screwed or brazed to the upper end of a vertical discharge pipe 6.

A screw-threaded coupling nut or ring 7 55 serves to unite the said parts together, and this nut or ring is also rounded internally to fit the spherically-shaped collar 5. The open bottom end 7 of the nut is flared outwardly at 9 to provide clearance for different settings or adjustments of the pipe. The lower end of pipe 6 may be smoothly finished to permit a telescopic or adjustable connection to be made with a floor pipe 10, and a union nut 11 and sealing gasket 12 may be used to 60 unite said parts at the joint.

The forwardly-extending portion of the elbow-shaped body 2 is provided with an annular flange 14 having a flat circular front face 15 adapted to abut against the outside 70 face of the inclined end wall 16 of a bath tub or other lavatory receptacle B opposite a round overflow opening 17 therein, see Fig. 7. A rubber sealing washer or gasket may be used between flange 14 and the tub wall 75 16, but this gasket is not shown in the drawing although commonly used. Overflow head 2 is also particularly constructed to deliver water into the tub. Thus, a short screw-threaded nipple or extension 18 is cast integrally with the top of head 2 and a water delivery spout 19 extends forwardly at the front side of the head, and the water passage 20 within the spout communicates with the vertical inlet 21 within nipple 18. A 80 combined hot and cold water valve body 22 is connected to nipple 18, and this valve body is clamped to tub wall 16 and has separate valve-handles 23 and 24 for controlling the hot and cold water supply leading to 85 inlet 21.

Delivery spout 19 is cast integral with the upper part of head 2 and lies in a horizontal plane at the top of or above the overflow intake opening 25 in said hollow head, so 90 that a normal overflow will not reach or submerge the spout. The spout is also long enough to extend through opening 17 in wall 16 and into the tub a substantial distance in front of said wall, so that the water may be 95 discharged downwardly into the tub apart from the wall. However, delivery spout 19 is completely covered and concealed by a rounded apron or hood 26 which forms an integral part of a perforated clamping disk or plate 27 made of porcelain, enameled metal or vitreous material. The body of 100 this perforated clamping member 27 is pref-

erably concavo-convex and of substantial thickness to withstand the application of pressure and clamping strains at its center, and an annular flange 28 is provided at the 5 rear side of this plate to fit within the round overflow opening 17 in the bath tub wall. When the clamping plate and hollow head are assembled upon opposite sides of the bath tub wall the delivery spout extends 10 through a relatively large opening 29 in the upper half of the porcelain disk and into the rounded projecting hood 26, and a clamping screw 30 extends through a central opening 31 in the porcelain plate where 15 screw engagement may be effected with a depending lug 32 within hollow head 2. The enlarged outer end 33 of screw 30 may be provided with an opening to permit a chain to be attached thereto, but this chain is not 20 shown in the drawings; it is commonly used to hold a rubber plug for use with the waste outlet 34 at the bottom of the tub.

Clamping plate 27 being made of porcelain or vitreous china it is unnecessary to 25 give the cast metal head and its delivery spout a highly polished finish because hood 26 and the body of the clamping plate completely conceals the spout and head viewed from the inside of the tub. The hollow 30 head being supported in the main from and by valve body 22, an excessive or very tight clamping pressure is not demanded of screw 30. Moreover, the ball joint 5 for the 35 overflow discharge pipe 6 permits flat and solid seating of the head against the tub and avoids strain or bind at the joint in making a connection with pipe 6 regardless of whether pipe 6 is perpendicular or more or

less inclined in respect to the bath tub and its attached overflow head 2.

40

Being aware of the Letters Patents granted to H. M. Weaver Nos. 906592 and 921574, for improvements in lavatories, I am only claiming herein the new and novel features and improvements which I have made in 45 view thereof.

That is to say, what I regard as my invention and discovery and desire to claim, is:

1. A combined water supply and overflow fixture for a bath tub, comprising a hollow cast-metal elbow open at its opposite ends having a water delivery spout extending therefrom, a vitreous china overflow plate having an opening in its upper half through which said spout is adapted to project into the tub, and provided with overflow openings in its lower half beneath said spout, and a clamping device adapted to attach said parts to the tub.

50

2. A combined water supply and overflow fixture for a bath tub comprising a hollow head having a depending outlet and a horizontal inlet and provided with a water delivery spout at its upper end extending forwardly beyond the inlet, a clamping plate having overflow openings in its lower half and a spout receiving opening and overhanging hood in its upper half, said spout extending beyond the front of the lower half of said clamping plate when the parts are fixed upon the tub.

55

In testimony whereof I affix my signature hereto this 18th day of September 1923.

ARTHUR I. FISCHER.
